SET MARK ELIMINATOR

Charles R. Beall, La Grange, Ga., assignor to
West Point Manufacturing Company, West
Point, Ga., a corporation of Alabama

Application March 4, 1949, Serial No. 79,643

9 Claims. (Cl. 139—111)

I This invention relates to looms, and more particularly to warp beam driving mechanism for looms.

During the weaving of textiles, the warp is commonly subjected to tension between the warp beam and the cloth take-up roller. In the case of many yarns, such as those spun of short fibers of wool or cotton, and extruded filaments, such as those of cellulose acetate, the warp tension causes the warp to "set" or stretch during overnight and other periods of shut-down.

When a loom is started after a period of shut-down, the first several filling threads, due to the set of the warp and the resulting slackening of tension, are not spaced similarly to the last filling threads inserted preceding shut-down. The resulting unevenness in filling thread spacing is known as a set mark, and is the cause of rejection of considerable quantities of cloth.

It is an object of the present invention to provide means, readily incorporated into conventional looms, adapted to eliminate the formation of set marks by restoring the desired warp tension when a loom is started after a period of shut-down.

It is a further object of this invention to provide means for turning back the warp beam of a loom when the loom is started, to increase the tension of the warp.

A further object of this invention is the provision of means for deactivating the let-off mechanism of a loom when the loom is started, and simultaneously turning back the warp beam of the loom to increase the tension of the warp.

A still further object is the provision of means for automatically turning back the warp beam of a loom when the loom is started, and the further provision of means controllable to vary the extent of such turn-back.

Other objects of the invention will be in part obvious and in part pointed out hereinafter.

The invention and the novel features thereof may best be made clear from the following description and the accompanying drawings, in which:

Figure 1 is a side view of a conventional loom, provided with a preferred embodiment of the present invention;

Figure 2 is an enlarged, detailed view corresponding to Figure 1, showing with greater particularity the means for turning back the warp beam;

Figure 3 is a partial section taken on the line 3—3 of Figure 1;

Figure 4 is a perspective view of the warp let-

off mechanism drive and the associated warp turn-back mechanism, and.

Figure 5 is a diagram of the turn-back mechanism control circuit.

5 Referring to the drawings, Figure 1 shows a preferred embodiment of the present invention, incorporated into a conventional loom, such as a Draper X Model loom, comprising the usual frame 10, the warp beam 11, and the shipper lever 12, 10 by displacement of which the loom is started and stopped. The warp beam 11 is positively driven to let off the warp in step-by-step fashion through the beam gear 13 by the pinion 14, actuated by the reciprocating motion of the rocker arm 15 extending from the lay rock shaft 16. The reciprocating motion of rocker arm 15 is transmitted to pinion 14 by the link 17 and the crank 18, operative to reciprocate the pawl carrier 19 and the pawl 20 associated therewith, and thereby displace the ratchet wheel 21 in step-by-step fashion. The ratchet wheel 21, in common with pinion 14, is mounted on the shaft 22. The above described let-off mechanism is well known, and does not constitute a part of the present invention.

25 On an extension of shaft 22 is affixed the turn-back ratchet wheel 23, with teeth arranged reversely to those of ratchet wheel 21. The push-pull rod 24 is slidably supported above turn-back ratchet wheel 23 by the guide 25, extending from frame 10. Shipper lever 12 is operatively connected to push-pull rod 24 in driving relationship by the rod 26 and the link 27, pivotally secured to opposed ends of the bell crank 28, mounted on frame 10 by means of the pivot 29. As best seen in Figure 2, the sleeve 30 is secured to push-pull rod 24 by the set screw 31, and the turn-back pawl 32 is pivotally supported above turn-back ratchet wheel 23 by the pin 33, retained between the flanges 34 extending downwardly from sleeve 30. The spring 35 is stretched between sleeve 30 and the tail 36 of turn-back pawl 32, and urges the turn-back pawl toward turn-back ratchet wheel 23. The stop 37 is provided on tail 36 to suitably limit the movement thereof.

40 The solenoid 38 is suitably mounted on the side of sleeve 30, and partially encloses the plunger 39, which is pivotally secured to the lug 40 extending from turn-back pawl 32, as by the pin 41. The flexible conduit 42 conducts the wires 43, 43' from solenoid 38 to the junction box 44, wherein solenoid 38 is connected to a source of power and through the flexible conduit 45 to the button switch 46, mounted, for the sake of convenience, 45 on the handle of shipper lever 12.

55

Also suitably secured to push-pull rod 24 and spaced therealong from sleeve 30 is the cam sleeve 47, from which depends the offset cam 48, positioned and adapted to engage and depress the cam following tail 49 of pawl 20 in passing thereover.

During the periods of shut-down, shipper lever 12 and the associated mechanism of this invention is in the position best shown in Figure 1, and in solid lines in Figure 2. The loom is started by moving the shipper lever 12 forward to the position shown in dotted lines in Figure 2. Movement of the shipper lever 12, it will be readily seen, causes corresponding movement of the rod 26, which movement is reversed in direction by bell crank 28 and transmitted through link 27 to the push-pull rod 24, causing the push-pull rod and the associated turn-back pawl 32 to traverse across the turn-back ratchet wheel 23, to the position shown in dotted lines in Figure 2. At the same time, the cam 48 is caused to traverse across the tail 49 of driving pawl 20.

When the loom is not operating, turn-back pawl 32 and cam 48 occupy the positions best shown in Figure 1, out of engagement, respectively, with turn-back ratchet wheel 23 and tail 49. In the course of the traverse of push-pull rod 24, occasioned by movement of shipper lever 12 to start the loom, turn-back pawl 32 successively engages turn-back ratchet wheel 23, displaces the turn-back ratchet wheel in the direction of the arrow 50, and moves out of engagement with said ratchet wheel to assume the position shown in dotted lines in Figure 2, where it remains while the loom is operating. Simultaneously, the cam 48 engages and depresses the tail 49 of pawl 20, thereby maintaining pawl 20 out of engagement with ratchet wheel 21 until the cam passes beyond the tail and assumes the final position shown in dotted lines in Figure 2, where it remains during the operation of the loom. When the loom is stopped by returning shipper lever 12 to the "off" position, the push-pull rod traverses to the left as shown, turn-back pawl 32 clicks over turn-back ratchet wheel 23 to resume its former position, and cam 48 passes over the pawl 20 to resume its former position.

It has been found that by restoring the warp tension prevailing before shut-down, upon starting the loom, the spacing of the first few filling threads inserted on starting up is substantially identical with that of the last few filling threads inserted before shut-down, and the formation of a set mark is obviated. The amount of turn-back necessary to return the warp to the tension prevailing before shut-down will, of course, vary with the type of yarn being woven, the duration of the shut-down, and other variables. It has been found that a moderately experienced operator can readily gauge the amount of turn-back necessary to accurately adjust the warp tension and prevent formation of set marks.

The throw of push-pull rod 24 and the vertical spacing of turn-back pawl 32 relative to the turn-back ratchet wheel 23 are desirably adjusted to effect an operative throw of the turn-back pawl corresponding to the maximum displacement of the warp turn-back mechanism likely to be needed under normal conditions expected to be encountered. Similarly, the operative length of the cam 48 is suitably adjusted to deactivate the pawl 20 during the engagement of the turn-back ratchet wheel by the turn-back

pawl. The operative throw of turn-back pawl 32 is conveniently varied downwardly from its maximum by means of solenoid 38. To effect this adjustment, the operator may, in starting the loom by means of shipper lever 12, depress button switch 46 during a portion of the travel of the shipper lever, thereby energizing solenoid 38 and causing the turn-back pawl to be held out of engagement with the turn-back ratchet wheel during the corresponding portion of the traverse of the turn-back pawl. Release of the button switch 46 during the remainder of the movement of the shipper lever allows the turn-back pawl to fall back and engage the turn-back ratchet wheel during the remaining portion of its traverse. In this manner, the operator may vary the amount of turn-back effectuated by movement of shipper lever 12, as may in his judgment be necessary. It will be apparent that the operative throw of the turn-back pawl may be made adjustable in other ways, mechanically or otherwise. Similarly, it will be apparent that other suitable means may be provided for deactivation of the let-off mechanism drive.

In the event of a shut-down of such short duration as not to cause any set of the warp, it will be evident that the button switch 46 may be depressed during the entire throw of shipper lever 12, in this manner starting the loom without any turn-back of the warp beam. In the circumstance that more turn-back is needed than is provided by the maximum operative throw of the turn-back pawl 32, the necessary amount of turn-back may be secured by repeated manipulation of the shipper lever back and forth, and the corresponding repeated operation of the associated mechanism of this invention.

While the warp beam turn-back mechanism of this invention has been shown, in the specific embodiment illustrated, as associated with a specific type of let-off mechanism, it will be apparent to those skilled in the art that the turn-back mechanism may drive the warp beam independently, or in association with other let-off mechanisms.

It will thus be seen, that there has been provided by this invention an apparatus in which the various objects hereinbefore set forth, together with many practical advantages, are successfully achieved.

As various possible embodiments may be made of the mechanical features of the above invention, all without departing from the scope thereof, it is to be understood that all matter hereinbefore set forth or shown in the accompanying drawings is to be interpreted as illustrative and not in a limiting sense.

I claim:

1. In combination with a loom, a shipper lever whereby said loom is started and stopped, a warp beam, let-off mechanism whereby said warp beam is actuated to let off the warp, and means operable by said shipper lever to temporarily deactivate said let-off mechanism and simultaneously turn back said warp beam a predetermined distance when said shipper lever is displaced to start the loom.

2. The invention as defined in claim 1, including means for varying the extent of operation of said turn-back means.

3. In combination with a loom, a shipper lever whereby said loom is started and stopped, a warp beam, let-off mechanism whereby said warp beam is actuated to let off the warp, a ratchet in oper-

ative relationship with said warp beam, a pawl adapted to engage and displace said ratchet to turn back said warp beam, and means operable by said shipper lever to temporarily deactivate said let-off mechanism and simultaneously actuate said pawl when said shipper lever is displaced to start the loom.

4. The invention as defined in claim 3, including means for varying the operative throw of said pawl.

5. In combination with a loom, a shipper lever whereby said loom is started and stopped, a warp beam, let-off mechanism whereby said warp beam is actuated to let off the warp, a ratchet in operative relationship with said warp beam, a pawl adapted to engage and displace said ratchet to turn back said warp beam, a mechanical linkage between said shipper lever and said pawl operable to actuate said pawl when said shipper lever is displaced to start the loom, and means associated with said mechanical linkage for deactivating said let-off mechanism during the operation of said pawl.

6. The invention as defined in claim 5, including a solenoid in association with said pawl operable to withhold said pawl from engagement with said ratchet during energization of said solenoid.

7. In combination with a loom, a shipper lever whereby said loom is started and stopped, a warp beam, let-off mechanism including a driving ratchet and driving pawl whereby said warp beam is actuated to let off the warp, a turn-back ratchet in association with said driving ratchet and oppositely disposed relative thereto, a turn-back pawl positioned and adapted to engage and displace said turn-back ratchet to turn back said warp beam, a mechanical linkage between said shipper lever and said turn-back pawl operable to actuate said turn-back pawl when said shipper lever is displaced to start

the loom, and means associated with said mechanical linkage for deactivating said driving pawl during the operative throw of said turn-back pawl.

- 5 8. The invention as defined in claim 7, including a solenoid in association with said turn-back pawl operable to withhold said turn-back pawl from engagement with said turn-back ratchet during energization of said solenoid.
- 10 9. In combination with a loom, a shipper lever whereby said loom is started and stopped, a warp beam, a driving ratchet and driving pawl associated with said warp beam in driving relationship and adapted to rotate said warp beam
- 15 15 to let off the warp, a turn-back ratchet in association with said driving ratchet and oppositely disposed relative thereto, a turn-back pawl positioned and adapted to engage and displace said turn-back ratchet to turn back said warp beam, a mechanical linkage between said shipper lever and said turn-back pawl operable to actuate said turn-back pawl when said shipper lever is displaced to start the loom, a cam associated with said mechanical linkage adapted to engage and inactivate said driving pawl in the course of displacement of said shipper lever, and a solenoid in association with said turn-back pawl operable to withhold said turn-back pawl from engagement with said turn-back ratchet during energization of said solenoid.
